[57] CLAIM

The ornamental design for a putting aid for golfers, as
shown.

DESCRIPTION

FIG. 1 is a top perspective view of a putting aid for
golfers showing my new design;

FIG. 2 is a perspective view of the putting aid from
below;

FIG. 3 is a side elevation of the putting aid;

FIG. 4 is a plan view of the putting aid;

FIG. 5 is a sectional end view of the putting aid taken
on line 5—5 of FIG. 4; and

FIG. 6 is a sectional end view of the putting aid taken
on line 6—6 on FIG. 4.

Fig. 1.

Fig. 2.
